UNITED STATES PATENT OFFICE.

EDUARD PELICH, OF PRAGUE, CZECHOSLOVAKIA.

REVOLVING-CYLINDER AND RECIPROCATING-PISTON PUMP.

Application filed October 26, 1925, Serial No. 64,942, and in Czechoslovakia October 27, 1924.

The present invention relates to pumps for liquid and gaseous materials of the rotary-cylinder and reciprocating-piston type.

There are known pumps in which a number of hollow prismatic bodies slide relatively to each other within the hollow space of the main pump body, working spaces of varying volume being produced between the sliding bodies by means of a shaft having an eccentric journal. This shaft is formed with inlet and outlet passages which open into suction and discharge grooves provided in the eccentric journal. The two grooves communicate with the working spaces of the pump by passages provided in the body or casing in which the shaft rotates.

According to another known arrangement pistons of circular section are carried by a hollow frame which slides in two slideways of a rotating disc. The pistons move in a central body rotatable upon an eccentrically mounted journal so that the several working spaces communicate with suction and discharge passages arranged in the journal which also communicates with the inlet and outlet passages of the pump.

The object of the present invention is to provide a construction which affords certain advantages owing to the fact that the eccentric journal is arranged stationary but is adjustably mounted in the casing so that by turning said journal the capacity or rate of discharge of the pump may be varied. The distributing valve is arranged upon the periphery of a rotating disc which revolves in the distributor casing, which enables the sections of the suction and discharge passages to be made comparatively large and moreover simplifies the construction and connection of said passages. This advantage of the external arrangement of the distributing valve is particularly important in the case of very small pumps.

One construction embodying the features of the invention is shown in the accompanying drawings in which:

Fig. 1 is partly a central cross section and partly an end view of the pump,

Fig. 2 is an axial section showing the eccentric journal in its lower or zero position.

Fig. 3 illustrates the annular distributing device in section and the manner of adjusting the capacity of the pump by altering the position of the eccentric journal.

Fig. 4 illustrates a modified manner of adjusting the capacity of the pump.

A disc 1 is adapted to be rotated in the pump casing by being connected to a plate 2 operable by means of an external shaft or the like. The disc 1 is provided with a central prismatic hollow space 3. In this hollow space is adapted to slide a quadrangular frame 4. A prismatic body 5 is adapted to slide in the frame 4. A prismatic body 5 which may act as a pump plunger is rotatably mounted upon a stationary journal 6 which is mounted eccentrically in relation to the axis of the disc 1 in a cover 7 of the casing. The axes of the journal 6 and the disc 1 are parallel to each other. A pointer 8 playing upon a scale 9 arranged upon the outside of the cover 7 is fixedly connected to the journal 6.

During the rotation of the disc 1 the two inner members 4 and 5 are constrained to rotate about the journal 6, this rotation producing sliding motion of the member 5 within the member 4 and sliding motion of the member 4 within the disc 1. The two sliding motions are at right angles to one another and correspond to components of a sine line. Owing to the sliding movement of the members 5 and 4 four working spaces *a*, *b*, *c*, *d* of varying volumes are produced. These working spaces are connected by passages 11, 12, 13 and 14 with the outer periphery of the disc 1. The passages of the working spaces *c*, *d* are constituted by bores 13, 14 of circular section formed in the disc 1 and by oval openings 15, 16 in the frame 4. The passages 11, 12 of the working spaces *a*, *b* are constituted by radial bores in the member 1. The disc 1 is adapted to rotate in a distributor sleeve 17 which is fixedly mounted in the pump casing 18 and is provided with two oppositely arranged peripheral slots 19, 20 the slot 19 being in communication with the suction union 21 and the slot 20 being in communication with the discharge union 22 of the pump casing 18. The working spaces of the pump therefore communicate alternately with the suction 21 and discharge 22.

The capacity of the pump may be adjusted in two ways:

According to the first method of adjustment, the journal 6 is turned in a bore of the cover 7 which is arranged concentrically to the axis of the disc 1, as indicated in

Figs. 2 and 3. p in Fig. 3 indicates the centre of rotation of the disc 1 and the distributor sleeve 17 whilst o indicates the centre of the journal 6. On rotating the disc 1 in the direction of the arrow, 19 will constitute the suction passage of the distributor sleeve 17 whilst 20 will constitute the discharge passage. If the line po coincides with the line ij which is the centre line of 5 the distributing sleeve 17, the capacity of the pump is a maximum inasmuch as the total quantity drawn in by the pump is also discharged. If the journal 6 be shifted into the position o' , the working spaces of the 10 pump will still be in the suction period although they have passed the position i and have been brought into communication with the discharge passage 20, so that the pump will draw fluid from the discharge end during a portion i, i' of its suction stroke. Similarly, the working spaces will communicate with the suction passage 19 at the end of the pressure stroke after passing the position j , so that the pump will discharge back 15 into the suction passage during a portion j, j' of the pressure stroke. If the journal 6 be turned through 90° that is into the position o'' , the capacity of the pump will be nil, the amount drawn in being equal to the amount 20 discharged back into the suction. On turning the journal beyond the position o'' , the suction passage will be converted into the discharge passage and the discharge passage will act as the suction passage. The 25 capacity of the quantity discharged by the pump is therefore determined by the position of the journal 6, which may be read on the scale 9 by means of the pointer 8.

According to the second method of adjustment, the distance between the axes of the disc 1 and the journal 6 is varied, the stroke of each piston being equal to the double distance of the axes. In the diagram of Fig. 4, o indicates the centre of the journal 6 which may be rotated about the axis r in the cover 7; by turning the journal 6 the center of the journal 6 is varied between the two extreme positions 0 max. and 0 min. and the effective stroke is correspondingly 30 varied.

Both methods of adjustment may be used particularly in connection with oil pumps.

I claim:

1. In a revolving piston pump with reciprocating prismatic pistons arranged slidably at right angles to each other in a driven disc rotatably mounted in an outer casing, the inner prismatic piston being rotatably arranged on a journal eccentrically mounted 55 in the casing of the pump, the combination of distributing means on the outside of the rotatable disc, the suction and discharge passages of said distributing means being in communication with the suction and discharge 60 passages of the casing; openings in the rotat-

able disc in front of the working faces of the prismatic piston sliding in said disc, and openings in the said rotatable disc and in the said prismatic piston in front of the second, inner prismatic piston sliding in the 70 first named prismatic piston, said openings connecting the working spaces of both prismatic pistons with the passages of the distributing means.

2. In a revolving piston pump with reciprocating prismatic pistons arranged slidably at right angles to each other in a driven disc rotatably mounted in an outer casing, the inner prismatic piston being rotatably arranged on a journal eccentrically mounted 80 in the casing of the pump, the combination of distributing means on the outside of the rotatable disc, the suction and discharge passages of said distributing means being in communication with the suction and discharge passages of the casing, openings in the rotatable disc in front of the working faces of the prismatic piston sliding in said disc, and openings in the said rotatable disc and in the said prismatic piston in front of the second, inner prismatic piston sliding in the 85 first named prismatic piston, said openings connecting the working spaces of both prismatic pistons with the passages of the distributing means, and means for altering 90 the capacity of the pump by altering the eccentricity of the journal bearing the inner prismatic piston relatively to the axis of the distributor sleeve.

3. In a double acting valveless pump, a 100 casing having inlet and discharge passages, a journal eccentrically mounted in said casing, a prismatic body carried by said journal and slidably radially of said casing upon relative rotation of said casing and journal, 105 a second prismatic body enclosing said first body and slidably in said casing in a direction normal to the sliding movement of said first body and means for adjusting the position of said eccentric journal with respect to 110 the axis of said casing to vary the capacity of said pump.

4. The structure as in claim 3 wherein the means for adjusting the position of said eccentric comprises means to vary the eccentricity of said journal with respect to the axis of said casing.

5. A revolving cylinder and reciprocating-piston pump comprising in combination 115 a casing, a rotatable disc, a prismatic body adapted to slide radially in said rotatable disc, a second prismatic body adapted to slide radially in the first named prismatic body, the directions of movement of the two 120 sliding bodies being at right angles to each other, a journal eccentrically mounted in the casing of the pump, said journal carrying the two said prismatic bodies, a distributor sleeve surrounding said rotatable disc and 125 formed with peripheral suction and dis- 130

charge passages, and communication passages connecting the working spaces formed between the two sliding prismatic bodies and between the outer prismatic body and the rotating disc with said suction and discharge passages, substantially as described.

6. In a revolving cylinder and reciprocating-piston pump according to claim 5, the

provision of means for altering the capacity of the pump by altering the distance between 10 the center of the said journal and the center of the said rotating disc, substantially as described.

In testimony whereof, I have signed my name to this specification.

EDUARD PELICH.
